UNITED STATES PATENT OFFICE.

PAUL SCHMITZ, OF COLOGNE-NIEHL, GERMANY, ASSIGNOR TO WILHELM JUNGBECKER,
OF AACHEN, GERMANY.

USE OF RAWHIDE.

1,108,402.

Specification of Letters Patent. Patented Aug. 25, 1914.

No Drawing.

Application filed June 20, 1913. Serial No. 774,839.

To all whom it may concern:

Be it known that I, PAUL SCHMITZ, a subject of the King of Prussia, German Emperor, residing at Cologne-Niehl, in the 5 Kingdom of Prussia, German Empire, have invented certain new and useful Improvements in the Use of Rawhide, of which the following is a specification.

Envelops for balloons and certain parts of 10 aeroplanes or other flying machines made from raw hide present the advantage that they are very light and of almost unlimited durability; they are proof against the changes of temperature, they can support 15 shocks and they do not produce electricity and are not electrically sensitive. As material in the construction the hides are generally used at a raw dried state. The parts are treated by pressure, by drawing or in

similar manner. It is obvious, that the surface of the hide could be coated in a convenient manner if this should be necessary. The material can further be made ductile by any convenient treatment provided that the general character of the hide is not modified and the tough, hornlike property of the upper layer is not interfered with. 20 25

I claim:

An improved balloon envelop made of raw hide dried and pressed so that it adopts the 30 required form, substantially as described and shown and for the purpose set forth.

In witness whereof I have hereunto set my hand in the presence of two witnesses.

PAUL SCHMITZ.

Witnesses:

M. KNEPPERS,
BESSIE F. DUNLAP.
